US00D930845S

(12) **United States Design Patent** (10) **Patent No.:** **US D930,845 S**
Schmidt et al. (45) **Date of Patent:** **** Sep. 14, 2021**

(54) **APPARATUS FOR THERMOTHERAPY**

(71) Applicant: **Dermapharm AG**, Grünwald (DE)

(72) Inventors: **Colin Schmidt**, Jena (DE); **Qiong Zhang**, Püchersreuth (DE)

(73) Assignee: **Dermapharm AG**, Grünwald (DE)

(**) Term: **15 Years**

(21) Appl. No.: **29/699,192**

(22) Filed: **Jul. 23, 2019**

(30) **Foreign Application Priority Data**

Jan. 23, 2019 (EP) 006082137
